(57) **CLAIM**

The ornamental design for a power strip, as shown and described.

DESCRIPTION

FIG. 1 is a perspective view of a first embodiment of a power strip;

FIG. 2 is a front elevation view of the power strip shown in FIG. 1;

FIG. 3 is a rear elevation view thereof;

FIG. 4 is a right side elevation view thereof with the left side thereof being a mirror image of the right side;

FIG. 5 is a top plan view thereof;

FIG. 6 is a bottom plan view thereof;

FIG. 7 is a perspective view of a second embodiment of a power strip;

FIG. 8 is a front elevation view thereof;

FIG. 9 is a rear elevation view thereof;

FIG. 10 is a right side elevation view thereof with the left side thereof being a mirror image of the right side, with the top plan view thereof being the same as the top plan view in FIG. 5, and with the bottom plan view thereof being the same as the bottom plan view in FIG. 6;

FIG. 11 is a perspective view of a third embodiment of a power strip;

FIG. 12 is a front elevation view thereof;

FIG. 13 is a rear elevation view thereof;

FIG. 14 is a right side elevation view thereof with the left side thereof being a mirror image of the right side, with the top plan view thereof being the same as the top plan view in FIG. 5, and with the bottom plan view thereof being the same as the bottom plan view in FIG. 6;

FIG. 15 is a perspective view of a fourth embodiment of a power strip;

FIG. 16 is a front elevation view thereof;

FIG. 17 is a rear elevation view thereof;

FIG. 18 is a right side elevation view thereof with the left side thereof being a mirror image of the right side, with the top plan view thereof being the same as the top plan view in

(Continued)

FIG. 5, and with the bottom plan view thereof being the same as the bottom plan view in FIG. 6;
 FIG. 19 is a perspective view of a fifth embodiment of a power strip;
 FIG. 20 is a front elevation view thereof;
 FIG. 21 is a rear elevation view thereof; and,
 FIG. 22 is a right side elevation view thereof with the left side thereof being a mirror image of the right side, with the top plan view thereof being the same as the top plan view in FIG. 5, and with the bottom plan view thereof being the same as the bottom plan view in FIG. 6.
 In the drawings, the broken lines are for the purpose of illustrating portions of the power strip that form no part of the claimed design.
